UNITED STATES PATENT OFFICE

128,263

DESIGN FOR A DOLL

Josephine Ranney, Chicago, Ill.

Application March 10, 1941, Serial No. 99,451

Term of patent 7 years

To all whom it may concern:

Be it known that I, Josephine Ranney, a citizen of the United States, residing at Chicago, in the county of Cook and State of Illinois, have invented a new, original, and ornamental Design for a Doll, of which the following is a specification, reference being had to the accompanying drawings, forming a part thereof.

In the drawings, Fig. 1 is a front view of a doll embodying my new design. Fig. 2 is a side elevation.

I claim:

The ornamental design for a doll, substantially as shown.

JOSEPHINE RANNEY.
